(57) **CLAIM**

The ornamental design for a bottle, as shown and described.

DESCRIPTION

FIG. 1 is a top, front and right isometric view of a bottle, shown in an assembled state; the bottom, rear, left isometric view being a mirror image thereof.

FIG. 2 is a front elevation view thereof, the rear, right and left elevation views being identical.

FIG. 3 is a top plan view thereof, the bottom plan view being identical.

FIG. 4 is a cross section view taken along line 4-4 of FIG. 3.

FIG. 5 is a cross section view taken along line 5-5 of FIG. 3.

FIG. 6 is a top, front, right exploded view thereof, shown in a disassembled state.

FIG. 7 is a bottom, rear, left exploded view thereof.

FIG. 8 is a top, front, right isometric view thereof, wherein the bottle is shown independent of the cap and base features as well as the internal exemplary cap, showing aspects of the design not visible when these features are combined.

FIG. 9 is a bottom rear left isometric view thereof.

FIG. 10 is a front elevation view thereof.

FIG. 11 is a right side elevation view thereof.

FIG. 12 is a rear elevation view thereof.

FIG. 13 is a left side elevation view thereof.

FIG. 14 is a top plan view thereof; and,

FIG. 15 is a bottom plan view thereof.

The broken dash lines in the figures depict portions of the bottle that form no part of the claimed design.
